UNITED STATES PATENT OFFICE.

ERNEST W. SEAHOLM, OF DETROIT, MICHIGAN.

DESIGN FOR AN AUTOMOBILE RADIATOR CASING.

Application filed December 8, 1924. Serial No. 11,611. Term of patent 14 years.

To all whom it may concern:

Be it known that I, ERNEST W. SEAHOLM, a citizen of the United States, and a resident of Detroit, county of Wayne, State of Michigan, have invented a new, original, and ornamental Design for Automobile Radiator Casing, of which the following is a specification, reference being made to the accompanying drawing forming a part thereof.

In the drawing,

Figure 1 is a front perspective showing my new design, Figure 2 is a side elevation, Figure 3 is a cross section taken on the line 3—3 of Figure 1 and Figure 4 is a cross section taken on the line 4—4 of Figure 1.

I claim:

The ornamental design for an automobile radiator casing as shown.

ERNEST W. SEAHOLM.
